UNITED STATES PATENT OFFICE

JAMES E. EVANS, OF ROSCOE, CALIFORNIA

COMBINED GAS GENERATOR AND BURNER

Application filed January 30, 1929. Serial No. 336,196.

My invention relates to a combined gas generator, burner and illuminating appliance that is especially designed for household and domestic purposes.

5 The principal objects of my present invention are, to generally improve upon and simplify the construction of the existing forms of combined gas generators and burners; further to provide an appliance that is especially designed for generating gas from kerosene, distillate or other relatively light liquid hydrocarbons; further, to provide a combined gas generator, burner and illuminating appliance that may be conveniently 10 and economically employed in practically all forms of stove furnaces, water heaters and the like, and further, to provide an appliance of the character referred to that is relatively simple in construction, inexpensive of manufacture and which may be advantageously and 15 economically employed wherever it is desired to generate gas from liquid hydrocarbon and to burn said gas for heating or illuminating purposes.

20 25 With the foregoing and other objects in view, my invention consists in certain novel features of construction and arrangement of parts that will hereinafter be more fully described and claimed and illustrated in the accompanying drawings in which:

Fig. 1 is a top plan view of a burner embodying the principles of my invention.

Fig. 2 is a vertical longitudinal section taken thru the center of the burner.

30 35 Fig. 3 is an enlarged horizontal section taken on the line 3—3 of Fig. 2.

Fig. 4 is an enlarged vertical section taken on the line 4—4 of Fig. 1.

Fig. 5 is an enlarged horizontal section 40 taken on the line 5—5 of Fig. 2.

Fig. 6 is a side elevational view of a modified form of the burner with parts thereof broken away and in section.

45 Fig. 7 is a plan view of a modified form of the burner wherein a pair of independent vaporizing retorts are made use of.

Fig. 8 is a cross section taken on the line 8—8 of Fig. 7.

50 Fig. 9 is an elevational view of a modified form of the burner.

Fig. 10 is a horizontal section taken on the line 10—10 of Fig. 9.

Fig. 11 is a plan view of a further modified form of the burner.

Fig. 12 is a cross section taken on the line 12—12 of Fig. 11.

Fig. 13 is a vertical longitudinal section taken through the center of a further modified form of the burner.

Fig. 14 is a cross section taken on the line 14—14 of Fig. 13.

Referring by numerals to the accompanying drawings, and particularly to the form of burner illustrated in Figs. 1 to 5, inclusive, 60 65 10 designates a hollow box-like body that is preferably formed of cast metal and said body having enlarged end portions 11. The top plate of this hollow body 10 and its enlarged ends is provided with transversely disposed narrow slots 12 which function as gas emission slots, and these relatively narrow slots extend downwardly a short distance in the side walls of the body 10 and its enlarged ends.

70 75 Formed integral with the underside of the body 10 and extending from one end thereof to a point shortly past the longitudinal center is a housing 13 that encloses a mixing chamber 14, and the outer end of this housing is extended upwardly and inwardly to form a goose-neck 15 having an open end 16 that occupies a plane above the upper surface of the body 10.

80 85 Formed within the body 10 at the center thereof is a transverse partition 17 having outwardly curved side faces 18 and formed in the bottom plate of the body 10 adjacent to the lower end of this partition are apertures 19 that communicate with the mixing chamber 15.

90 95 Formed integral with the inner end of the housing 13 and within the mixing chamber 14 immediately below the openings 19 are outwardly curved walls 20 and formed through the side walls of the housing 13 adjacent to the outer ends of these curved walls are openings 21 that are normally closed by removable plugs 22.

When a series of the burner bodies are cooperatively associated or when gas is taken from the mixing chamber to an illuminat- 100

ing appliance or the like, plugs 22 may be removed and the ends of tubes or ducts, such as 23, are inserted in the apertures 21 and the gas from the mixing chamber 14 is deflected outwardly through the ducts by the curved faces of the wall or partitions 20.

Gas in passing from the mixing chamber 14 through the apertures 19 is deflected outwardly in opposite directions through the ends of the body 10 of the burner by the curved faces 18 of partition 17.

Arranged longitudinally above the body of the burner and supported at one end by a lug 24 that projects upwardly from the burner body, is a tubular retort 25, the free end of which carries a nozzle 26 in which is formed a relatively small tapered outlet orifice 27 and this nozzle is supported within a hood 28 that occupies a position directly in front of the open end 16 of goose-neck 15.

Secured to the rear end of the retort outside the supporting lug 24 is a fitting 29 to which leads a liquid hydrocarbon supply pipe 30, and arranged on the outer portion of the fitting 29 is a gland or stuffing box 31. Passing through this gland 31 and through the retort 25 is a rod 32, the forward end of which is tapered to form a needle valve 33, which latter controls the outlet aperture 27 in the nozzle 26. A threaded portion 34 of the rod 32 engages a correspondingly threaded portion of the fitting 29 and the outer end of rod 32 carries a handle 35.

Retort 25 occupies a slightly inclined position with its rear end lowermost and thus any liquid hydrocarbon that may accumulate within the retort will, by gravity, pass to the lower rear end of said retort.

In the use of the form of burner just described the burner body 10 and the retort 25 are heated with a torch or any other suitable means and liquid hydrocarbon is permitted to enter the retort through supply pipe 30.

Due to the heated condition of the retort 45 the liquid hydrocarbon will be converted into gas and as the needle valve 33 is withdrawn from the orifice 27 by manipulation of rod 32 the gas will discharge from the nozzle of the retort into goose-neck 15 and simultaneously with such discharge a certain amount of air will be drawn into the goose-neck and pass with the gas into the mixing chamber 14 and after passing therethrough this mixture of gas and air will pass upwardly 50 through the openings 19 and by the curved surfaces 18 said mixture will be caused to pass outwardly through the chambers within the burner body and said mixture will then pass through the narrow slots 12 and combustion of the mixture will take place on top of the burner body.

Inasmuch as the retort is positioned directly over the burner body said retort will be 60 maintained in a highly heated condition so

as to vaporize the liquid hydrocarbon that enters the retort through tube 30.

In the modified construction illustrated in Fig. 6, the burner body is constructed separately from the housing 13 and the two parts are detachably connected by means of a threaded stud 36 that projects downwardly from the center of the burner body and which engages in a threaded aperture formed in the top of the housing 13. This arrangement enables the same form of mixing chamber and gooseneck to be utilized with different forms of burner bodies.

In the modified construction illustrated in Figs. 7 and 8 a substantially circular burner body 37 provided with gas emission slots 38 in its upper plate is provided with a diametrically arranged partition 39, thereby forming two separate chambers 40, and formed on one side of the body 37 are two 85 gooseneck members 41, one for each chamber 40.

Overlying the burner body 37 is a pair of retorts 42, the free ends of which are arranged to discharge into the open ends of the gooseneck members and the rear ends of the retorts are connected by a fitting 43, and connected to the latter is a liquid hydrocarbon supply pipe 44.

The fitting 43 is provided with glands 45 through which pass stems 46 of the valves that control the outlet openings in the nozzles carried by the forward ends of the retorts.

In this form of burner the two retorts may be utilized independently or where both retorts are being used at the same time and the outlet orifice from either retort becomes closed by carbon accumulations the gas generated in the closed retort will pass to and through the other retort so that the burner remains in operation even though one of the retorts is temporarily out of service.

In the modified construction illustrated in Figs. 9 and 10 a goose-neck 47 is formed integral with and extends downwardly and outwardly from one side of the body 48 of the burner and formed on the interior of the burner body immediately in front of the opening into the goose-neck is a horizontally disposed V-shaped member 49 that functions as a deflector to cause the mixture of gas and air that enters the body from the goose-neck to be deflected laterally in both directions and thereby discharge evenly through the outlet slots in the top of the burner body.

In the lower portion of the goose-neck 47 is a petcock 47^a which permits any liquid hydrocarbon that results from condensation of gas passing through the goose-neck to be readily withdrawn therefrom.

In the modified construction illustrated in Figs. 11 and 12 a pair of burner bodies 50 and 51 are arranged side by side, said bodies being of any size and shape desired and connected by a tubular member 52. Arranged

above the burner body 51 is a retort 53 and the nozzle thereof is arranged to discharge into the open end of a horizontally disposed goose-neck 54 that is formed integrally with and projects laterally from the corresponding end of the burner body 50. In this construction the burner bodies 50 and 51 occupy the same horizontal plane and a relatively large flame area is produced.

10 In the modified construction illustrated in Figs. 13 and 14 a burner body 55 has formed integrally with its top plate a centrally arranged longitudinally disposed duct 56 and formed in the wall above said duct is a series 15 of gaseous emission slots 57. One end of the duct 56 terminates in a goose-neck 58 that is arranged immediately below a larger goose-neck 59 that extends outwardly, upwardly and inwardly from the burner body 55.

20 Arranged directly in front of the open ends of the goose-neck members 58 and 59 is a combined hood and bracket 60 in which are formed apertures 61 that are positioned directly opposite the open ends of the goose-neck members and which apertures are adapted to receive the nozzle 62 that is carried by the forward end of a retort 63 and which latter occupies an inclined position directly above the duct or chamber 56.

30 When this form of burner is utilized for producing a maximum degree of heat, the retort 63 has its nozzle 62 positioned in the uppermost one of the apertures 61 so as to discharge into the open end of the goose-neck 35 59 and thus gas and air will be delivered to the chamber within the burner body 55. When it is desired to produce only a relatively small amount of heat the retort is adjusted so that its nozzle is positioned in the lower one of the apertures 16 and when so positioned gas and air will discharge into the goose-neck 58 that leads to duct 56 and the flames of the burning gas issuing from the slots 57 will act as pilot lights to light 40 the burner when the same is utilized for producing a maximum degree of heat, and at the same time said pilot lights will develop sufficient heat within the pilot to vaporize the liquid hydrocarbon that is delivered thereto, 45 thus producing sufficient gas to maintain the pilot lights.

The burners embodying the principles of my invention may be used singly or in combination and said burners may be made in 50 various sizes and shapes depending upon the purpose for which they are intended.

A further desirable and economical feature of my invention is the construction and arrangement whereby a highly inflammable 55 gas is generated from gasoline, distillate or like liquid hydrocarbons and which gas may be taken to points remote from the generator and utilized for illuminating or heating purposes.

60 Thus it will be seen that I have provided

a combined gas generator, burner and illuminating appliance that is relatively simple in construction, inexpensive of manufacture and very effective in performing the functions for which it is intended.

70

It will be understood that minor changes in the size, form and construction of the various parts of my improved combined gas generator, burner and illuminating appliance may be made and substituted for those herein shown and described without departing from the spirit of my invention, the scope of which is set forth in the appended claims.

75

I claim as my invention:

1. In a combined gas generator, burner and illuminating appliance, an elongated hollow body provided with enlarged ends, the top plate of which body is provided with narrow transversely disposed slots, a mixing chamber on the underside of said hollow body, a goose-neck projecting upwardly and inwardly from the outer end of said mixing chamber, a retort arranged above the hollow body, and provided at its forward end with a valve controlled orifice that discharges into the open end of the gooseneck, the inner end of the mixing chamber having communication with the central portion of the chamber within the hollow body, and a transversely disposed partition formed in the center of said hollow body, the side faces of which partition are curved upwardly and outwardly away from each other.

80

2. In a combined gas generator, burner and illuminating appliance, an elongated hollow body having enlarged end portions, the top plate of which hollow body is provided with narrow transversely disposed slots, a retort arranged above said hollow body, the forward end of which retort is provided with a valve controlled outlet orifice, a housing formed on the underside of said hollow body, the outer portion of which housing terminates in an upwardly and inwardly curved goose-neck, the open end of which is positioned adjacent to the valved outlet in the end of the retort, there being openings formed in the bottom plate of the elongated body above the inner end of the housing, a partition formed within the elongated body 110 between said openings, which partition is provided with upwardly and outwardly curved side faces, there being openings formed in the side walls of the housing adjacent to the inner end thereof, and curved deflecting members formed within said housing adjacent to the openings in the side walls thereof.

85

95

100

105

110

115

120

125

130

3. In a combined gas generator, burner and illuminating appliance, an elongated hollow body provided in its top plate with a plurality of narrow transversely disposed slots, a housing on the underside of said body, the outer end of which housing is curved upwardly and inwardly and provided with an

open upper end, the chamber within said housing constituting a mixing chamber, a transversely disposed partition in the center of the hollow body, the side faces of which partition are formed with curved deflecting surfaces, and there being openings formed in the bottom plate of the hollow body for establishing communication between the mixing chamber and the chambers within the hollow body on opposite sides of the partition therein.

4. In a combined gas generator, burner and illuminating appliance, an elongated hollow body provided in its top plate with a plurality of narrow transversely disposed slots, a housing on the underside of said body, the outer end of which housing is curved upwardly and inwardly and provided with an open upper end, the chamber within said housing constituting a mixing chamber, a transversely disposed partition in the center of the hollow body, the side faces of which partition are formed with curved deflecting surfaces, there being openings formed in the bottom plate of the hollow body for establishing communication between the mixing chamber and the chambers within the hollow body on opposite sides of the partition therein, there being openings formed in the inner portions of the side walls of said housing, and deflecting members arranged within said housing adjacent to the openings in the side walls thereof.

In testimony whereof I affix my signature.
JAMES E. EVANS.
